OF HOPEDALE, MASSACHUSETTS, A CORPORATION OF MAINE.

DROP DEVICE OR DETECTOR FOR LOOMS.

1,116,003.

Specification of Letters Patent.

Patented Nov. 3, 1914.

Application filed December 14, 1912. Serial No. 736,660.

To all whom it may concern:

Be it known that I, FRANCIS E. ASHTON, a citizen of the United States, residing at Exeter, in the county of Rockingham and 5 State of New Hampshire, have invented an Improvement in Drop Devices or Detectors for Looms, of which the following description, in connection with the accompanying drawings, is a specification, like letters on 10 the drawings representing like parts.

The invention to be hereinafter described relates to devices or detectors employed in looms for detecting breakage or abnormal condition of a warp thread, and upon such 15 detection to cause actuation of suitable means for stopping the loom. As well understood by those skilled in the art, these drop devices or detectors are hung upon the warp threads, and are usually constructed 20 with a warp eye through which one or more warp threads pass, so that upon breakage or abnormal slackness of a warp thread, the drop device or detector supported thereby will drop to a position to cause the 25 actuation of means to stop the loom. To draw the individual warp threads through the eyes of the series of drop devices or detectors by hand is a slow and expensive operation, and means have been devised for 30 performing this office by in mechanical operation. To enable the drawing-in needle to properly pass through the warp eye of the drop device or detector and engage and draw a warp thread therethrough, it has been found 35 necessary to provide means to present the drop devices or detectors individually to the action of the needle. This has been done by means of a feeding device in the form of a worm which is passed through a suitable 40 feed opening in the drop devices or detectors, so that upon rotation of the worm the drop devices or detectors would be offered individually for the action of the needle, and to facilitate a proper separation and in- 45 dividual presentation of the drop devices or detectors, these feed openings have been formed as keyhole openings. If, however, these key-hole openings are in line when the drop devices or detectors are hung upon 50 their support or placed in their guiding devices in the loom, it is found that lint will accumulate therein and eventually form a rope-like strand extending through the series of drop devices or detectors, with the 55 result that upon the occurrence of a warp

fault, the drop device or detector that should make manifest this fault and stop the loom, will remain supported by this rope-like strand of lint and fail to operate the stopping means. It therefore becomes necessary 60 that these feed or key-hole openings in adjacent drop devices or detectors shall be so placed that when the drop devices or detectors are in the loom, said openings shall be out of line. Thus, while lint may still ac- 65 cumulate in said openings during the loom operation, there will be an interruption of any rope-like lint formation, and upon the occurrence of a warp fault, the drop device or detector may drop and assume control 70 of the warp stop motion. When, however, these feed or key-hole openings are thus placed in different positions in the drop devices or detectors, it is impossible to pass the feed worm through the series of drop de- 75 vices or detectors without first lining up such openings.

With these generally-stated facts in mind, the aims and purposes of the present invention will best be made clear from the following description and accompanying drawings of one form of means for carrying the invention into practical effect, it being understood, however, that the invention is not limited to the details thereof, but may be 85 varied within the true scope of the invention as pointed out by the claims.

In the drawings:—Figure 1 shows in side elevation a series of drop devices or detectors and one way in which the same may be 90 leveled or lined up to present the feed or key-hole openings in line for the passage of the feed screw or other feeding means; Fig. 2 is a section of Fig. 1 on the line 2—2, Fig. 1; Fig. 3 is a section of Fig. 1 on the 95 line 3—3, Fig. 1; Fig. 4 shows one of the drop devices or detectors in front elevation; and Fig. 5 shows a like view of an adjacent drop device or detector.

The drop devices or detectors may be 100 variously formed and of any suitable material, but for the purpose of exploiting the invention, they are herein shown as formed of flat strips of metal 1, each having the usual warp eye 2 for the passage of a warp thread, and a guide slot or opening 3 by which they may be suitably guided by the usual guide bar in the loom. Obviously, the guide slot 3 may be varied in position 105 with respect to the warp eye 2, and indeed 110

the drop devices or detectors may be guided in their rising and falling movement by any suitable means in the loom, as will be clearly understood.

- 5 The drop devices or detectors, are each provided with a feed opening 4, which, when a worm is employed for individually separating and presenting the drop devices or detectors to the action of the drawing-in needle, are preferably formed of key-hole shape, as shown. The feed or key-hole opening 4 in one drop device or detector in a series of such drop devices or detectors, is located at a different position with respect 10 to the warp eye 2, than is the feed or key-hole opening of the next adjacent drop device or detector. In the form of the invention shown, the position of the feed or key-hole opening in one drop device or detector is 15 shown nearer the warp eye in a vertical direction than is the feed or key-hole opening of the next adjacent drop device or detector, so that when the series of drop devices or detectors are hung upon the guide bar in the loom, the key-hole openings in adjacent drop devices or detectors will be 20 out of line, and the objectionable rope of lint extending between the said detectors cannot be formed, and proper operation of 25 the stop motion may be initiated by the dropping of any one of said drop devices or detectors. The position of the key-hole openings in adjacent drop devices or detectors when in the loom is well indicated by 30 the full and dotted lines in Fig. 2.

It will be noted by reference to the drawings that the non-circular portion 5 of the key-hole openings 4 in adjacent drop devices or detectors extend in different directions, 40 whereby when the drop devices or detectors are similarly arranged upon the feed worm of the drawing-in machine, the said drop devices or detectors will travel along the worm in separated relation, as the worm is 45 revolved, thereby presenting each drop device or detector individually to the drawing-in needle, as will be clearly understood by those skilled in the art.

As hereinbefore suggested, it is necessary 50 to bring the key-hole openings of all the drop devices or detectors in line before the feed worm can be passed therethrough, and to this end the present invention contemplates providing the drop devices or detectors of a series with a leveling notch which 55 in coöperation with a leveling trough or block to be described, serves to secure the desired alinement of the key-hole opening for the entrance of the worm. As one 60 means to this end every alternate drop device or detector of a series is provided with a notch 6, which for the purpose of identification, may be known as the leveling notch, 65 such term, however, being one of identification only and not of limitation; the con-

struction being such that when a series of such drop devices or detectors are placed in a leveling trough or block, to be described, the key-hole opening of all the drop devices or detectors will assume such alinement that 70 the feed screw may readily be passed through the series.

The leveling trough or block in one of its preferred forms, is indicated in Figs. 1 and 3, and comprises a base portion 7 provided with upwardly projecting sides 8, 8, preferably separated a distance sufficient to receive the lower ends of the drop devices or detectors, as indicated by Figs. 1 and 3. Extending longitudinally between the sides 8, 8, is a leveling rib or projecting flange 9 adapted to receive the leveling notches 6 of alternate drop devices or detectors, the construction being such that when a series of drop devices or detectors, alternate ones 85 of which have the leveling notch 6, are placed with their ends in the trough or leveling block 7, as indicated in Fig. 3, those drop devices or detectors unprovided with the leveling notch 6 will be raised 90 higher than the alternate drop devices or detectors having the leveling notch 6. Inasmuch therefore, as the drop devices or detectors provided with the leveling notch have the key-hole opening closer to the 95 warp eye than those without the leveling notch, the key-hole opening of all the drop devices or detectors will be brought into alinement, as indicated by Figs. 1 and 3.

In operation, a series of drop devices or 100 detectors of the general character described, are placed upon a supporting bar 10, Fig. 1, the width of which is preferably less than the length of the guide openings 3, by an amount substantially equal to the depth of 105 the leveling slot 6, and the leveling trough or block 7 is then moved along beneath the series of drop devices or detectors, thus alining the key-hole openings as described, and the feed screw is then progressively 110 entered into the alined key-hole openings. Obviously, instead of moving the leveling trough or block progressively beneath the series of drop devices or detectors, the latter may be placed in the leveling trough and 115 all lined up or leveled so that the feed screw may enter the alined openings, and instead of entering the screw as indicated in Fig. 1, its end 12 may be entered first, the essentials in these respects being that the drop 120 devices or detectors be provided with a leveling notch in such position that when placed in a leveling trough provided with means for coöperation with said leveling notches, the series of drop devices or detectors may be leveled to bring the feed or 125 key-hole openings of all into alinement for entrance of the feed device.

In the drawings the leveling trough or block 7 is shown as having the rib or flange 130

9 extending beyond the end thereof, and this is found to be a good practical form of the leveling trough or block, especially when it is to be moved along beneath the series 5 of detectors, as described, but obviously this is not necessary in all cases and may be omitted where the leveling trough is made longer to receive and level a greater number 10 of drop devices or detectors. It will be clear to those skilled in the art, also that the leveling notch may be differently shaped or differently formed and be located at other points if desired and that variations of the leveling trough or block may 15 be made within the true scope of the invention, as defined by the claims. It will be noted also that the formation of the leveling notch is so far removed from the warp eye of the drop devices or detectors, that in 20 the operation of the loom it does not meet, chafe, or otherwise injure the warp threads leading from an adjacent row or series of drop devices or detectors, it being understood that in usual practice there are two 25 series of drop devices or detectors arranged in parallel relation transversely of the loom; and by forming the leveling notch adjacent an end portion of the drop devices or detectors, injurious weakening of 30 the drop devices or detectors is avoided.

What is claimed is:—

1. A drop device or warp detector for looms, having a warp eye for the passage of a warp thread, a feed opening, and a 35 leveling notch extending from an outer edge into the body of the device or detector.

2. A drop device or warp detector for looms, having a warp eye for the passage of a warp thread, a key-hole feed opening, and 40 an open leveling notch extending from the edge of the device or detector.

3. A drop device or warp detector for looms, having a warp eye for the passage of a warp thread, a feed opening, and a leveling notch, said leveling notch being located 45 adjacent an end portion of said detector or drop device.

4. In a device of the character described, a series of drop devices or detectors, each 50 having a warp eye, and feed opening, said feed opening in adjacent drop devices or detectors being located at different positions with respect to the warp eye, alternate drop devices or detectors being provided 55 with a leveling notch, and means adapted to engage the leveling notches of said alternate drop devices or detectors and unnotched portions of the other drop devices or detectors for lining up the feed openings.

5. In a device of the character described, a series of drop devices or detectors each having a warp eye and key-hole feed opening, said key-hole feed opening being differently 60 located in adjacent drop devices or detectors,

a part only of the drop devices or detectors of the series being provided with a leveling notch, and means for engaging the unnotched drop devices or detectors and the leveling notches of the other drop devices 70 or detectors for lining up the drop devices or detectors with the key-hole openings in substantial alinement.

6. In a device of the character described, a series of drop devices or detectors each having a warp eye and a key-hole opening, the key-hole openings in adjacent drop devices or detectors being arranged at different positions with respect to the warp eye, and the non-circular portions thereof extending in 80 different directions, and alternate drop devices or detectors of the series being provided with a leveling notch.

7. In a device of the character described, a series of drop devices or detectors each having a warp eye and feed opening, said feed openings being out of alinement, and leveling means to act upon the exterior of the drop devices or detectors to bring the feed 85 openings into alinement.

8. In a device of the character described, a series of drop devices or detectors each having a warp eye and a feed opening, the said feed openings being at different distances from the warp eye in adjacent drop devices 95 or detectors, alternate drop devices or detectors being provided with a leveling notch, and a leveling trough or block adapted to receive said drop devices or detectors and bring the feed openings into alinement.

9. A drop device or detector for looms, having a warp eye, a key-hole opening, and an open leveling notch extending into an edge portion of the drop device or detector.

10. An assemblage of independent thread-engaging loom elements, such as drop wires, detached heddles or the like, having each a threading opening and a releasing opening, successive releasing openings being differentially arranged to present an alternate variation in form between successive members, means to support the assembled members with releasing openings out of alinement, and means to exteriorly engage an edge portion of and support said members with the said openings in alinement.

11. An assemblage of independent thread-engaging loom elements, such as drop wires, detached heddles or the like, each having a 120 threading opening and a releasing opening, means to support the members of the series with the releasing openings out of alinement, and means to exteriorly engage and support the same with said openings in 125 alinement.

12. An assemblage of independent thread-engaging loom elements, such as drop bars, detached heddles or the like, each having a threading opening, means for supporting 130

the same with the threading openings in line, and means to exteriorly engage and support the same with the threading openings out of line.

5 13. An assemblage of independent thread engaging loom elements, such as drop bars, detached heddles or the like, each having a threading opening and alternate ones having in addition alining means uniformly spaced from the said threading openings.

14. An independent detached heddle having a threading opening, a releasing open-sided notch and an alining opening.

In testimony whereof, I have signed my name to this specification, in the presence 15 of two subscribing witnesses.

FRANCIS E. ASHTON.

Corrections in Letters Patent No. 1,116,003.

It is hereby certified that in Letters Patent No. 1,116,003, granted November 3, 1914, upon the application of Francis E. Ashton, of Exeter, New Hampshire, for an improvement in "Drop Devices or Detectors for Looms," errors appear in the printed specification requiring correction as follows: Page 4, lines 12-13, for the words "open-sided notch" read *opening*; same page, line 13, for the word "opening" read *open-sided notch*; and that the said Letters Patent should be read with these corrections therein that the same may conform to the record of the case in the Patent Office.

Signed and sealed this 24th day of November, A. D., 1914.

[SEAL.]

R. F. WHITEHEAD,

Acting Commissioner of Patents.
